DIGESTER UNIT

Joaquin J. de la Roza, Sr., New York, N. Y.

Application March 29, 1944, Serial No. 528,537

2 Claims. (Cl. 92—18)

1

This invention relates to improvements in a digester unit and refers more particularly to an assembly consisting of an inner rotatable digestion vessel supported within an outer stationary vessel, the inner vessel having an inlet opening for introduction of the material to be treated and an outlet for discharge of the stock after digestion. In the annular space between the inner and outer vessels is circulated a heating medium for accurately controlling the temperature within the inner vessel.

Between the vessels at their ends are seals which prevent communication between the contents of the inner vessel and the jacket and automatically compensate for differences in elongation caused by uneven heating.

The novelty resides primarily in providing a tubular screw conveyor digester in one section and grinding means in a separate section of the same vessel or in a separate vessel for mechanically reducing the material undergoing digestion.

The digester unit is particularly adapted for digestion of fibrous substances in the presence of chemicals at elevated temperatures for the production of uniformly high grade cellulose pulps.

The digester offers facilities for uniformly treating fibrous material for a longer period of time in a continuous operation, utilizing a much shorter vessel than is necessary for the same results when a tubular screw conveyor or mechanical reduction is not employed.

There is provided in a single vessel means for digesting fibrous substances in the presence of chemicals at high temperature and simultaneously mechanically reducing the bundles of fiber.

A further advantage of the design is the fastening of the conveyor screw to the internal wall of the digesting vessel, thereby eliminating the objectional effect of a rotating screw which scrapes and damages the fibre.

In addition, the digestion unit combines facilities for more uniformly and effectively impregnating the fibrous material with chemical liquor while mechanically breaking up the fibrous bundles and disseminate more effectively and separate the incrustations from the fiber.

The digester unit eliminates to a great extent by-passing of undigested portions of the material undergoing treatment and substantially preventing insufficient or inadequate treatment of portions of the digesting mass, thereby increasing uniformity of the product.

It eliminates irregularities in the product produced by stopping and starting of the digester, a

2

practice which normally seriously affects the homogeneity of the mass; the action of the tubular screw conveyor preventing migration of the material longitudinally of the chamber.

5 In the accompanying drawing which forms a part of the instant specification, and is to be read in conjunction therewith and in which like reference numerals are used to indicate like parts in the various views,

10 Fig. 1 is a sectional side view of a digester in which the chemical treating and mechanical reduction sections are combined in a single vessel;

15 Fig. 2 is a fragmentary view of a two-vessel unit in which the mechanical reduction is performed in a separate vessel.

Referring first to the digestion unit shown in Fig. 1, an outer stationary cylindrical vessel 10 is supported upon foundations 11 by means of 20 supports 12. At the ends of the vessel 10 are flanges 13 to which are bolted covers 14 and 15. An opening 16 in cover 14 serves as an inlet for material charged through pipe 17. In cover 15 is an opening 18 through which the material is 25 discharged after digestion. A discharge pipe 19 is bolted to the opening.

Within the stationary vessel 10 is a concentric cylindrical vessel of smaller diameter 20 which has a common axis with the outer vessel. The 30 inner vessel which encloses the digestion space is rotatable within the outer stationary vessel. The inner vessel is supported upon sets of flanged rollers 21 supported within the outer stationary vessel. Pairs of the rollers are offset somewhat 35 from the low point of the inner digestion vessel and are flanged to roll upon tracks or rings 22 which surround the periphery of the vessel at its ends and at necessary intervals along its length where the vessel needs support.

40 As a source of power for rotating the inner vessel there is shown a motor 23 supported with its gear transmission upon a foundation 24. Upon the shaft of the motor is mounted a pinion 25 which meshes with a second pinion 26 on stub shaft 27. Gear 28 on the stub shaft meshes 45 with a ring gear 29 surrounding and fixedly attached to the shell of the inner vessel. Suitable stuffing boxes surround shaft 27 where it enters the auxiliary housing 30 which surrounds gear 28 and communicates with the annular space between the two vessels. A fluid medium circulated in the annular space is introduced through pipe 31 and is discharged through pipe 32. On the inner face of flanges 13 are 50 annular rings 33 which form annular cylinders 34.

Reciprocatably in cylinders 34 are seal rings 35 whose inner ends contact the outer faces of flanges 20a of the inner rotating cylinder assuring a pressure-tight seal between the inner rotating vessel and the outer stationary vessel regardless of elongation differences of the respective vessels due to differential heating. Pressure behind seal rings 35 for effecting the proper degree of contact between the rings and the flange 20a is produced either by fluid pressure or by suitable compression springs, details of which form no part of the present invention.

The digestion space within the inner vessel is divided into sections by a perforated plate 36. Within the section to the left of this partition is shown the vanes of a continuous screw 37. In the section to the right of partition 36 is a compartment equipped with a liner of material resistant to impacting elements shown diagrammatically at 39. These impacting elements may be tubes, balls or rods or any type of objects which tumble about in the compartment and serve to break down or reduce mechanically the material undergoing digestion. A second perforated plate 40 prevents the impacting elements from escaping from the compartment but permits passage of the broken up fibrous material from the mechanical reduction compartment into the discharge pipe 18 of the digester.

In the modified type of digester unit shown in Fig. 2 the single concentric vessels have been replaced by a pair of concentric vessels connected by a transfer pipe 41. Instead of separating the inner vessel into two sections by the perforated plate 36, one digester includes the section in which the chemical treatment of the fibrous material is performed, the succeeding digesting vessel corresponds to the compartment for mechanically reducing the chemically treated mass identical in construction to the compartment to the right of the perforated partition in 36 in Fig. 1. By numbering corresponding parts of the digester units shown in Figs. 1 and 2 with corresponding numerals best indicates the similarities between the structural elements. In Fig. 2 the outer stationary casing is shown at 10, the inner rotating vessel at 20. The supports and drying mechanism is, of course, identical. Attached to the inner wall of the inner vessel is a continuous screw 37 which serves to advance the material as the vessel rotates.

Referring to the operation of the digester shown in Fig. 1 material to be digested is introduced through pipes 17 and inlet opening 16 in the cover 14 of the stationary digester. This inlet opening communicates with a chamber in the inlet end of the stationary vessel which is in alignment with the open end of the inner rotating vessel. Rotation of the inner vessel causes the material to be picked up by the flights 37 of the screw attached to the inner wall of the vessel advancing material slowly longitudinally of the vessel as it rotates. The digestion liquor is introduced to the material prior to its introduction.

As a result of the breaking down of the material resulting from the reaction of the digestion liquor and the mechanical effect of the tumbling as it advances through the vessel, on arrival at perforated plate 36 its particle size is sufficiently small to pass the perforations in the plate. In the compartment or section of the inner vessel to the right of plate 36 the mass is brought in intimate contact with the impacting elements 39 where it is mechanically reduced and disintegrated to the desired amount. As the pulp stock

it is discharged through the perforations in plate 40 which are of a size which will permit ready passage of the treated mass, but prevents passage of the impacting elements. After passage through plate 40 the pulp is discharged through opening 18 and pipe 19. After leaving the digester the pulp mass may be treated in any desirable manner.

The operation with respect to the digester unit shown in Fig. 2 is similar to that shown in Fig. 1 with the exception that during the digesting period the mass passes through two separate digestion zones, one limited to substantially chemical treatment and the other primarily to mechanical reduction. The two separate stages in Fig. 2 are joined by transfer pipe 41. The details of both the chemical digester and mechanical digester of Fig. 2 is diagrammatically shown with many of the parts eliminated in the interest of simplicity as their details are more clearly shown and described in the single digester unit shown in Fig. 1.

For controlling the temperature of digestion within the inner vessel in both the single unit 25 and in the double unit a fluid heating medium is circulated in the annular space surrounding the inner vessel through pipes 31 and discharged through pipes 32. This fluid medium is preferably steam where heating is desired, but may be any suitable fluid such as oil or its derivatives or other heating fluids. Where refrigeration is desirable in the digestion of any material a brine may be circulated or other type of refrigerant may be circulated through the annular jacket.

While the digester unit has been described in connection with the treatment of fibrous materials, it may be employed as well in the digestion of any substances where the material is to be chemically treated and mechanically disintegrated and the temperatures of digestion accurately maintained.

It is contemplated also that in the treatment of fibrous substances there may be interposed between the mechanical and chemical stages as shown in Fig. 2, a deliquefying treatment as by pressing or rolling.

While it has been proved preferable to incline slightly the digesters so that drainage will readily take place, it is a feature of the digester units that they need not be placed at any appreciable slant or inclination in order to produce the desired forward movement or advancement of the digesting mass as this is taken care of by the effect of screw 37. The screw flights also have the effect of uniformly mixing the mass with the treating liquor. By attaching the internal screw to the wall of the inner vessel, the objectionable effect of a rotating screw which scrapes and damages fiber is avoided.

From the foregoing it will be seen that the invention is one well adapted to attain all of the ends and objects herein set forth together with other advantages which are obvious and which are inherent to the structure.

As many possible embodiments may be made of the invention without departing from the scope thereof, it is to be understood that all matter herein set forth or shown in the accompanying drawing is to be interpreted as illustrative and not in a limiting sense.

Having thus described my invention, I claim:

1. A continuous multistage digester unit comprising substantially horizontal rotatable inner and stationary outer imperforate vessels having fluid-tight seals therebetween and means for cir-

culating a fluid medium in the annular space between the vessels, the former of said vessels enclosing a digestion space, a perforated partition dividing the digestion space into separate sections, said perforated partition adapted for passing digested material therethrough, an open screw affixed to the inner wall of one section for advancing material, impacting objects within the other section of the digestion space, and inlet and discharge pipes at opposite ends of the digestion space.

2. A digester unit comprising substantially horizontal concentric cylindrical vessels having a common axis and a sealed annular space there-

5
10

between, means for circulating a fluid medium through the annular space, the inner vessel rotatable within the outer stationary vessel, said inner vessel enclosing the digestion space, a perforate partition dividing the digestion space into separate sections, inlet and discharge pipes at opposite ends of the digestion space, an open screw affixed to the inner wall of one section for advancing the material introduced thereto upon rotation of the inner vessel, and mechanical impacting objects within the other section of the vessel.
